UNITED STATES PATENT OFFICE.

BIRGER JOHNSEN, OF LOS ANGELES, CALIFORNIA, ASSIGNOR TO ZELZAH CARBONATOR CO., OF LOS ANGELES, CALIFORNIA, A CORPORATION OF CALIFORNIA.

DISPENSING APPARATUS.

Application filed November 16, 1922. Serial No. 601,327.

To all whom it may concern:

Be it known that I, BIRGER JOHNSEN, a citizen of the United States, residing at Los Angeles, in the county of Los Angeles and 5 State of California, have invented new and useful Improvements in Dispensing Apparatus, of which the following is a specification.

This invention relates to water carbonating apparatus, and has for an object to provide an apparatus of simple and substantial construction and including one primary draft valve with a single operating lever whereby several desirable functions in the 10 distribution of the liquids and gases in the apparatus may be readily obtained.

It is an object of the invention to provide a carbonating apparatus having a water cooling chamber wherein water to be carbonated is chilled before it is saturated with carbonic acid gas thus to secure an economy 15 in the amount of gas absorbed as there is a greater coefficient of saturation as the temperature of the water descends.

Another object is to provide means for the 20 prevention of loss of trapped gas, means being provided to return the trapped gas to the water main where it is returned with the water into the water cooling coil where it is 25 absorbed and loss is prevented.

Another object is to provide a carbonated 30 water dispensing apparatus wherein means are provided for automatically admitting fresh water to the carbonator concurrently 35 with the drawing of carbonated water; the fresh supply being substantially equal to the amount of carbonated water drawn off. Further, in this connection, it is an object to provide a carbonator having capacity for 40 holding a desired discharge of carbonated water, for instance several glasses, so that when a single glass or a couple of glasses of water are drawn there is still a charge of carbonated water in the carbonator and this 45 charge is constantly replenished as carbonated water is drawn.

Another object is to provide means for preventing the loss of gas by the provision of a positive valve shut-off. Another object 50 is to use a single medium as a gas inlet and as a carbonated water discharge, the alternate use of which is controlled by the single means draft valve.

Another object is to provide for the discharge of air that may form from water

trapped in the outlet pipe, this accumulated air being discharged by the draft valve as it passes through the initial portion of its opening movement.

Further, an object is to provide for the use 60 of the main draft valve to secure a discharge of clear fresh water or for use in the discharge of carbonated water.

A further object is to provide a carbonator 65 in which gas pressure is turned on or is effective during all of the period of time that the valve is closed.

Other objects and advantages will be made manifest in the following specification of an embodiment of the invention illustrated in the accompanying drawings, 70 wherein—

Figure 1 is a plan of a carbonator, the shell of which is shown in horizontal section.

Fig. 2 is a vertical central section of the 75 carbonator.

Fig. 3 is a front elevation of the carbonator.

Fig. 4 is a vertical section and partial elevation of a fragment of one of the gas 80 columns.

Fig. 5 is a plan of one of the baffle buttons, and Fig. 6 is a side elevation of one of the baffle buttons detached from the gas 85 column.

Fig. 7 is a plan of one of the button shelves, and Fig. 8 is a transverse section through one of the shelves.

Fig. 9 is a longitudinal section through the draft valve body, and shows in plan the 90 draft valve plug.

Fig. 10 is a cross section on line 10—10 of Fig. 9.

Fig. 11 is a cross section of Fig. 9.

Fig. 12 is a diagrammatic view showing 95 two cross sectional planes through the draft valve and illustrating the discharge water port closed and the supply gas port opening.

Fig. 13 is a diagrammatic and cross sectional view showing the valve ports illustrated in Fig. 2 in the second position; and illustrating the port positioned to discharge trapped air from the carbonator through the outlet of the draft valve and showing the gas supply cut off.

Fig. 14 is a diagrammatic and sectional view showing the valve plug in its third 105 position for the supply of fresh water to the cooling coil and showing the gas discharging valve port arranged for the con- 110

current discharge of carbonated water while the carbonator is being supplied with fresh water.

Fig. 15 is a diagrammatic and sectional view showing the valve plug in its reversed position to effect a discharge of clear water and concurrently closing other ports.

Fig. 16 is a detail section showing the position of the valve plug to discharge fine or "fizz" forming stream of carbonated water.

The present carbonator is shown as embodying any suitable form of insulated casing or jacket 2 preferably constructed to contain cooling water W up to any suitable level and this water may be occasionally drained off or replenished in any suitable manner. In front of the casing 2 is arranged a mug or glass platform 3 and in this is arranged a small valve 4 having three-way ports so that excess liquid accumulating on the platform 3 may be drained straight down through a waste pipe 5. The drain valve or cock 4 is adapted to be turned to an angular position so as to communicate with a duct 6 to the inner end of which is connected a siphon pipe 7 terminating close to the bottom of the water containing casing 2. To drain the casing, it is only necessary to turn the valve 5 to such position as to communicate the duct 6 with the waste pipe 5 and the greater head of water in the casing 2 will cause it to initiate a discharge through the pipe 7 and subsequently the water will be siphoned to the bottom of the casing.

Arranged in the front of the casing and at a suitable distance above the glass platform 3 is a main draft valve body 10 having a downturned discharge spout or nozzle 9 and an inwardly projecting end 8 which is disposed in the upper portion of the casing 2.

In the lower portion of the casing there is mounted a distributing chamber 11, the bottom of which may be provided with a drain cock 12 and extending from the top of the distributing chamber is a centrally disposed pipe or tube 13 which, by my present invention, serves the dual functions of gas inlet means and a carbonated water outlet means; the upper end of the tube 13 being connected at 14 to the contiguous end of the draft valve body 10.

Secured to the inner end of the draft valve body is a water pipe 15 preferably extended in the form of a helix 15^a for convenience and compactness surrounding the gas and carbonated water tube 13. The lower end of the water pipe is turned upwardly at 15^b and is connected to the bottom of a head or water chamber 16.

Gas distributing and baffling means are provided, and such means are here shown as comprising a series of vertically or other-

wise arranged columns 17 in the form of tubes having elbows 18 at their lower ends connected suitably as by unions 19 and nipples 20 to the upper portion of the chamber 11 which is here shown as of spherical form. The upper ends of the carbonating columns 17 are also provided with elbows 21 connected as by unions 22 and nipples 23 to the lower portion of the water chamber 16 which is shown as spherical.

The apparatus provides for the initial cooling of the water in the water coil 15^a before the water passes therefrom to the columns 17 wherein the water becomes saturated with the carbonic acid gas, and this precooling is obtained as by means of the water W in which may be submerged ice so as to keep the temperature of the water down to that of iced water.

Gas which is supplied through the gas pipe 13 passes from the distributing chamber 11 into the several upright columns 17, and for the purpose of increasing the area of contact between the descending streams of water flowing from the water head or chamber 16, means are provided in the gas columns to effect the diversion of the water and the gas into various circuitous passageways and against interposed baffles to cause the intimate contact of the gas and water. A preferred form of baffle means is shown in detail in Figs. 4 to 8 inclusive in which there is shown a form of shelf or baffle represented as a ring 25 having concaved sides and a central aperture 26 of relatively constricted area. A series of these baffle shelves is arranged in each of the columns 17, and between each of the shelves there is disposed an intermediate barrier or baffle in the form of a disc 27 having convexed sides and which is herein termed a button.

Each disc is provided on its upper and lower surfaces with a plurality of spacing lugs 28, the lugs of the lower faces resting upon the next lower barrier and shelf forming elements 25, while the lugs on the upper faces of the buttons 27 support the next higher shelf 25. The concave faces of the shelves 25 and the substantially concentric or parallel faces of the buttons 27 form constricted passageways from bottom to top of the gas columns and thus provide for a path of traverse of very considerable length through which the gas ascends and the water descends and this insures the effective and rapid saturation of the water.

As clearly shown in Fig. 9, the draft valve body 10 is provided on one side with a nipple 30 for attachment of a gas supply pipe 31 125 and on the other side is provided with a nipple 32 for attachment of a fresh water supply pipe 33. The nipple 31 is the terminus for a gas passage 30^a and the nipple 32 is the terminus for a water passage 32^a 130

which is shown in Fig. 10 as being in a lower plane than the gas passage 30^a, which latter terminates at its inner end contiguous to the tapered surface of a valve plug 35 having 5 a rotative fit in a conical seat 36 provided therefor in the outer end of the valve body 10. The draft valve plug 35 is adapted to be operated as by means of a draft lever or handle 37, and the plug is constantly pressed 10 to a liquid tight fit on its seat as by a spring 38.

Paralleling the gas passage 30^a is a water passage 40, the front end of which terminates contiguous to the valve plug 35 and to the 15 rear end of which is connected the water tube 15. In Fig. 10 the water passage 40 is shown as in vertical alinement with the water passage 32^a so that a water port 41 provided in the valve plug 35 can be disposed, as shown in Fig. 14, to connect the 20 water supply pipe 33 to the water supply passage 40. Concurrently with the setting of the water port 41 of the valve 35, as shown in Fig. 14, a discharge of carbonated 25 water through the draft valve is provided for from the central tube 13. The outlet end of this tube is shown in Fig. 14 as connected with a discharge passage 42 extending longitudinally through the valve body 30 10 and terminating in the valve seat 36 so that there can be registered with the carbonated water discharge passage 42, a discharge port 43 formed in the valve plug 35 and which, preferably, has a branched discharge 35 end, the branches being shown at 43^a and 43^b which are adapted to register with outlet 40 passages 44, provided in the spout of the draft valve body.

When the valve plug 35 is adjusted to provide 40 for the discharge of carbonated water through the port 43 from the passage 42, there is at the same time a stream of fresh water being supplied through the port 41, as shown in the sketch in Fig. 14, the fresh 45 water passing to the cooling coil tube 15.

A feature of the invention consists in providing for the supply of gas from the gas pipe 31 to the carbonated water conduit or passage 42; the gas supply passing from 50 the pipe 31 to the gas passage 30^a. The valve plug 35 is provided with a port 46 so formed and arranged that when the valve plug is in the cut-off or nondischarging position, Fig. 12, the gas port 46 will open communication from the gas passage 30^a to the 55 passage 42 and gas will then flow from the source of supply the gas bottle B, Fig. 3, to the lower distributing chamber 11.

The gas supplied to the chamber 11 will 60 rise through the distributing and retarding columns 17 so as to charge the water therein and leaving the latter in readiness to be discharged by the movement of the valve handle 37 to its discharge position shown 65 in Fig. 14.

It may be desirable to obtain a discharge of the carbonated water in a fine froth or fizz stream, and in which case the valve handle 37 can be swung slightly so as to bring the discharge end 43^b of the plug 43 70 over a central discharge aperture 45, Fig. 16; this aperture being of comparatively small diameter and resulting in the discharge of the carbonated water in a fine stream. 75

When the water is standing in the discharge pipe 13, there is an accumulation of air in the upper end of the pipe 13 and in its connection 14 and in the passage 42 connected thereto, and it is desired to discharge 80 this accumulated air during the initial opening movement of the valve lever 37 and for which purpose the valve plug 35 is provided with a gas venting port 48, Fig. 13, which is adapted to move into register with the passage 42 and with the central fizz discharge outlet 45. The air is discharged instantly 85 while the port 48, just described, is crossing the ends of the passage 42 and the port 45. 90

To economize in the consumption, and to avoid waste, of carbonic acid gases, I provide for the transfer of gas which may collect in the gas pipe 13 above the charged water therein back into the apparatus and 95 preferably into the fresh water supply passageways, and for this purpose a cross duct 49, Fig. 13, is provided and this duct is designed to move into register with the outlet 100 passage 42 momentarily and at the same instant to register with the fresh water passage 32^a thereby permitting the flow of the gas into the apparatus to be absorbed instead of escaping unused through the discharge spout. 105

It may be desirable, occasionally, to draw clear fresh water, uncarbonated, from the draft valve, and Fig. 15 shows the valve plug 35 positioned with its handle thrown rearwardly to the maximum degree at which time a port 50 in the valve is in communication with a water supply passage 32^a and registers with the outlet 45 in the spout, thereby permitting the discharge of fresh water and at the same time interrupting free 110 passage through the several remaining ports in the valve plug. 115

Further embodiments, modifications and changes may be resorted to within the spirit of the invention as here claimed. 120

What is claimed is:

1. A carbonated water apparatus comprising a cooled water vessel, a draft valve body on the upper portion of said vessel, a distributing chamber arranged in the lower 125 portion of the vessel, a water chamber in the upper portion of the vessel, means connecting the distributing chamber and the water chamber, and a gas supply and carbonated water outlet pipe connected to the 130

distributing chamber, said pipe connecting with said valve.

2. A carbonated water apparatus comprising a water vessel, a draft valve body mounted in the upper portion of said vessel, a distributing chamber arranged in the lower portion of the vessel, a water chamber at the upper portion of the vessel, a gas supply pipe connected to the distributing chamber, and a draft valve provided with means for controlling supply of gas to the gas supply pipe and for controlling the discharge of carbonated water back through the said gas supply pipe.

15 3. A carbonated water apparatus comprising a water vessel, a draft valve connected to the vessel at the upper portion thereof, a distributing chamber arranged in the lower portion of the vessel, a water chamber at the upper portion of the vessel, means connecting the gas chamber and the water chamber, and a gas supply pipe connected to the distributing chamber and to said valve body, said gas supply pipe providing a 20 means for discharging the carbonated water.

4. A water carbonating apparatus comprising water and gas mixing means including a water supply tube and a gas supply tube, and a single valve for controlling the 25 supply of a carbonating gas and the dis-

charge of carbonated water; said valve having means for providing for the return of trapped gas to a water supply connection leading to said means to prevent the loss of the trapped gas as waste from the spout of the valve said tubes being connected to the valve.

5. A carbonated water apparatus comprising a water vessel, a distributing chamber arranged in the lower portion of the vessel, a water chamber arranged in the upper portion of the vessel, spaced conduits connecting the distributing chamber and the water chamber, a draft valve mounted in the said vessel and having a water supply tube arranged in the vessel and disposed in a helix between the upper and lower chambers so that the contents will be cooled by liquid in the chamber, said tube being attached to the upper chamber, and a gas supply tube connected to the valve and extending down in the vessel and connecting with the lower chamber, said gas supply tube providing for the discharge of carbonated water, gas and carbonated water flow therein being 50 controlled by said valve.

In testimony whereof I have signed my name to this specification.

BIRGER JOHNSEN.
